United States Patent Office

Des. 192,061
Patented Jan. 9, 1962

192,061

COMBINED LUBRICANT AND COOLING UNIT

Thomas R. Thomas, 151 W. Passaic St., New York, N.Y.

Filed Aug. 30, 1960, Ser. No. 62,072

Term of patent 14 years

(Cl. D65—1)

FIG. 1 is a front elevational view of a combined lubricant and cooling unit showing my new design.

FIG. 2 is a side elevational view taken from the left of FIG. 1.

FIG. 3 is a rear elevational view thereof.

FIG. 4 is a side elevational view taken from the right of FIG. 1.

FIG. 5 is a top plan view thereof.

The bottom view is plain.

I claim:

The ornamental design for a combined lubricant and cooling unit, as shown and described.
